DENTAL CHAIR BASE

Dwight A. Booth, 7906 SE. 13th Ave.,
Portland, Oreg. 97202

Filed Feb. 15, 1973, Ser. No. 332,606

Term of patent 14 years

Int. Cl. D6—06, 01

U.S. Cl. D6—194

FIG. 1

FIG. 2

FIG. 3

FIG. 4

FIG. 1 is a perspective view of a dental chair base showing my new design;

FIG. 2 is a left side elevational view, the right side being a mirror image;

FIG. 3 is a front elevational view; and

FIG. 4 is a left side elevational view on a reduced scale of the base in extended position.

I claim:

The ornamental design for a dental chair base, as shown and described.
